UNITED STATES PATENT OFFICE.

HENRY LUND SMITH, OF PATERSON, NEW JERSEY.

VISION SHIELD.

Application filed January 29, 1921. Serial No. 440,866.

To all whom it may concern:

Be it known that I, HENRY LUND SMITH, a citizen of the United States, residing at Paterson, in the county of Passaic and State 5 of New Jersey, have invented certain new and useful Improvements in Vision Shields, of which the following is a specification.

This invention relates to vision shields for vehicles designed to prevent the glare of the 10 lights of an approaching vehicle at night from embarrassing the driver's vision. I have already disclosed a novel vision shield of this class in a copending application filed by me under the Serial Number 411,724, the 15 salient feature of which consists in a plurality of translucent areas with a clear-vision space between them, said areas being in that case afforded by members whose adjoining portions were offset, to wit, by the 20 members being arranged in inclined planes and substantially parallel. In the present case one of my objects is to provide a shield that is simpler and less expensive than, if perhaps it does not afford quite as broad 25 scope of clear visibility, as my former shield, and this I accomplish by arranging the translucent members all in the same plane, as by forming slits in a sheet or plate. Another object is to provide an improved 30 means for supporting such a shield or equivalent device.

In the drawings,

Figure 1 is a rear elevation of one form of the improved shield and its supporting 35 means, the latter being shown attached to a vehicle wind-shield;

Figure 2 is a side elevation, partly in section, of what is shown in Figure 1;

Figure 3 is a sectional view on line 3—3, 40 Figure 2;

Figure 4 shows another form of the shield in front elevation;

Figure 5 is a sectional view on the line 5—5, Figure 4; and

Figures 6 and 7 show blanks which go to 45 form the supporting means.

The shield is formed as shown in Figures 1 and 2 from a plate or sheet *a* composed of material that is capable of transmitting 50 light rays without permitting objects to be seen distinctly therethrough, or translucent, such as ground or frosted or suitably colored glass, or, preferably, celluloid or equivalent infrangible substance. Transverse horizontal slits *b* are formed in the sheet or plate *a*

to afford the clear-vision areas, leaving translucent vanes or members *a'* between them.

As shown in Figures 4 and 5 the shield is formed of a sheet *c* of similar, that is to say, translucent material, being also provided 60 with horizontal clear-vision areas *d*. But, in this case in order to increase the range of clear vision through any one clear-vision area the material of the sheet adjacent each such area is beveled at a forward and downward incline, preferably both above and below said area. This is done by severing the sheet on horizontal lines nearly to the lateral margins of the sheet, which will leave translucent vanes or members *e*, and also 65 severing the sheet short distances from and at the ends of these lines of severing, upwardly as to the alternate lines, as at *f*, and downwardly as to the remaining lines, as at *g*, and then bending the lower edge portion 70 of each vane in one direction and the other edge portion in the opposite direction and each at an incline to the plane of the sheet, see Figure 5. The front of the sheet is the face appearing in Figure 4 or to the left in 75 Figure 5.

So far as the shield proper, already described, is concerned, it is not material how it is mounted. But I prefer to provide the following supporting means therefor: *i* is a 80 clamp having a suitable clamping device (such as a set screw *j*) and also having an angular projecting arm *k*. A telescopic fixture is provided as follows, one member 85 thereof being adapted to be pivoted on the arm *k* and the other having attached thereto the shield proper. The first or stem member of the fixture is formed from an elongated blank *l* of sheet material having its one end forked and provided with laterally extending projections *m*, the body of the blank being formed with pairs of opposite holes *n* and each projection with a hole *o*. The blank is folded on a longitudinal central line 90 so as to bring the holes in each pair of holes *n* and also the holes *o* in registry with each other, and this produces the stem member marked *p* in Figures 1, 2 and 3. Studs *q* having enlarged protruding heads *r* occupy the holes *n* and form rivets to clamp the 95 two layers of the stem together. The second or shield carrying member is formed from an elongated blank *s* of sheet material having pairs of opposite ears *t* and one end *u* reduced in width and bifurcated, and also hav- 100

105

110

ing holes v in the ears and pairs of longitudinal slots w : see Figure 6. This blank is folded on a longitudinal central line into channeled form so that the slots w in each 5 pair register with each other, the ears t being bent outwardly and so as to stand in the same plane (Figure 3). Rivets x passed through the holes of the ears t and the shield secure the latter to the member s . Member 10 s forms a sheath for the stem member p the projecting ends of whose studs r are made to occupy the slots w . The shield carrying member is then adjustable on the stem member, longitudinally, to the limits of 15 play of the studs in the slots. The telescopic fixture carrying the shield is attached to the arm k of clamp i by having its upper end, which is in effect forked, arranged to receive said arm, a screw bolt y being passed 20 through the holes o and a hole in the arm and having a nut z and between its head z' and the forked head of the telescopic fixture a spring 2 so that an adjustable clamping pressure is exerted on the arm k . The re- 25 duced end-portion u of the shield carrying member affords a handle whereby it may be adjusted on the stem member p or the entire fixture may be pivotally adjusted on the screw bolt y to any desired angle. A wind- 30 shield of an automobile, to which the clamp i is attached, is indicated at 3.

In either form of shield proper the glare of an approaching light is reduced by the translucent areas and yet the driver has a 35 clear vision of the road through the clear-vision areas. The slits may be quite narrow and yet the shield affords a very sensibly better view ahead than if its whole field were translucent, because of the shifting of the 40 shield and the driver's eyes relatively to each other due to the vehicle's motion over the road; but I prefer to increase the range of vision more or less close to and ahead of the vehicle, for which purpose the shield shown 45 in Figure 4 is better than that shown in Figure 1.

A quite important element of my present invention is the portion of the shield which I have marked 4 and which embraces a 50 translucent field uninterrupted by clear-vision areas and having an area approximating at least the combined area of two or more of the adjoining translucent and clear-vision portions formed by the parts a'

and intervening slits. The device being in 55 the operative or upright position the structure s a may be shifted up or down to bring the field 4 in line with the normal direction taken by the driver's eyes—more or less distant or approximately horizontal. The 60 field 4 then comes into play as a more restful medium of vision than would be the slitted field below it, which latter he makes use of in glancing at the road more or less near and ahead of the vehicle from time to 65 time,

Having thus fully described my invention, what I claim as new and desire to secure by Letters Patent is:—

1. A vision shield including a plurality of 70 translucent vanes having substantially flat surfaces arranged in substantially the same plane and having a clear-vision area intervening between them, one of the vanes also having a surface forming an angle with its 75 first-named surface inclined forwardly and downwardly from the observer's side of the shield.

2. A vision shield including a plurality of 80 translucent vanes arranged in substantially the same plane and having a clear-vision space intervening between them, the portion of one vane adjoining the other being bent into a plane inclined forward and downward from the observer's side of the shield. 85

3. A vision shield formed of a translucent plate having narrow elongated clear-vision openings therein.

4. A vision shield formed of a translucent plate having narrow elongated substantially horizontal and parallel openings therein and extending across the plate short of the ends thereof, the material of the plate at one horizontal side of each opening being bent out of the plane of the plate whereby 95 to form a clear-vision opening of greater width when viewed from one angle than when viewed from another.

5. A vision shield including two contiguous vision fields, one comprising alternating translucent and clear-vision areas and the other embodying an area approximately as great as a plurality of said translucent and clear-vision areas and being uninterruptedly translucent throughout the whole of its 100 said area.

In testimony whereof I affix my signature.
HENRY LUND SMITH.
